UNITED STATES PATENT OFFICE.

MARTIN PEARSON, OF LOS ANGELES, CALIFORNIA.

STABILIZER FOR AEROPLANES.

Application filed March 16, 1925. Serial No. 15,980.

To all whom it may concern:

Be it known that I, MARTIN PEARSON, a citizen of the United States of America, residing at Los Angeles, county of Los Angeles, State of California, have invented a certain new and useful Stabilizer for Aeroplanes; and I do hereby declare the following to be a full, clear, and exact description of the invention, such as will enable others skilled in the art to which it appertains to make and use the same.

An object of this invention is to provide a simple means for maintaining the equilibrium of an aeroplane while in flight. To that end, I employ a propeller that is adapted to be moved in a circle, and to automatically change its position and be actuated to resist an accidental diverting of an aeroplane from a predetermined flying position. That is, when an aeroplane is accidentally tipped to a side or end position in which it is liable to fall, the stabilizer propeller will automatically be moved into a position and driven to restore and preserve the equilibrium of the aeroplane.

Another object is to provide a simple and efficient means for maintaining the equilibrium of an aeroplane while in flight which also can be utilized to provide auxiliary power to propel the aeroplane.

Other objects, advantages and features of invention may appear from the accompanying drawings, the subjoined detailed description and the appended claims.

The accompanying drawings illustrate the invention.

Figure 1 is a side view of a stabilizer constructed in accordance with this invention showing it attached to an aeroplane.

Fig. 2 is an enlarged fragmental longitudinal section through the stabilizer.

Fig. 3 is an enlarged fragmental section through the tail end and rudder of the stabilizer, showing therein an electrical switch in open position.

Fig. 4 is a cross section on line 4—4, Figs. 1 and 3.

Fig. 5 is an enlarged fragmental section through a portion of the propeller support showing therein a detail of a rotary electrical connection.

Fig. 6 is a cross section on line 6—6, Fig. 5.

Fig. 7 is an enlarged view of an aeroplane assumed to be falling, showing the position of the stabilizer when operating to resist

the fall of the aeroplane and to also turn its wings to a horizontal position.

Fig. 8 is an end view on small scale of another aeroplane assumed to be falling, additionally illustrating the position and operation of the stabilizer in resisting the fall of the aeroplane, and its action in turning the aeroplane so that the wings are in a horizontal instead of a vertical position.

Fig. 9 is a view of an aeroplane assumed to be falling head downward; showing the stabilizer operating to resist the fall and turn the aeroplane back to a normal flying position.

Fig. 10 is a diagrammatic view of the electrical motor, battery switches and wiring of the stabilizer; showing the switches in open position.

Fig. 11 is a view analogous to Fig. 3, showing the switch in a closed position.

The stabilizer 12 is attached to the body 13 of an aeroplane and preferably arranged on the top thereof and adjacent to cock pit 14.

The aeroplane shown in the drawings is provided with the usual wings 13^a, propeller 13^b and rudder 13^c. These parts are old and well known in the art and are therefore not shown or described in detail.

On the top of the body 13 is arranged a hollow support 15 that is secured by bolts 16 to a platform 17, and a ball bearing housing 18 is secured on the top end of the support.

Stationary disks 19 and 20 are arranged on opposite sides of a rotary disk 21; and suitable ball bearings are arranged between the disks so that the disk 21 can have relatively free rotary movement.

The disk 21 is threaded and secured to the threaded portion of a hollow spindle 22 that extends down into the support 15; and also has its upper end extending through the housing 18; and a motor housing 23 is secured to the upper end of the spindle.

An electrical motor 24, having a shaft 25 extending through a roller bearing 26, is secured in the housing 23; and secured to the shaft 25 is the stabilizer propeller 27.

Preferably the support 15 is arranged perpendicular to the longitudinal axis of the aeroplane body 13 and is rigidly secured in that position as previously stated; and is also braced by rods 28 that extend from an annular flange 29 on the housing 18 to the

platform 17 to which they are secured by eye bolts 30.

This arrangement of the support causes it to incline rearwardly toward the tail end of the aeroplane at an angle of about fifteen degrees.

The purpose of inclining the support rearwardly is to enable the weighted end of the stabilizer tail 31 to normally hold the propeller 27 toward the head end of the aeroplane; so that normally the shaft 25 is parallel with the longitudinal axis of the body 13.

A tail 31 has one end secured to the motor housing 23; and integral with the free end of this tail is a ball cage 32 that is arranged to extend about thirty degrees upward from the longitudinal axis of the tail; so that normally the heavy ball 33 therein will lay at the end of the cage adjacent the tip end of the tail 31.

Spring mounted electrical contacts 34 and 35 are secured at the other end of the cage 32; and normally they are disengaged; but they are arranged to be moved into contact when the ball 33 is forced by gravity into engagement with an insulation block 36 that is carried by the spring contact 34.

In other words when the cage 32 is tilted into a position in which gravity will cause the heavy ball 33 to roll into engagement with the block 36 it will press the contact 34 into engagement with the contact 35 and establish a circuit between the motor 24 and a battery 46.

A tail rudder 37 is secured to the tip end of the tail 31 and cage 32, and as its purpose is well understood it is not described in detail.

An insulation plug 38 is threaded into the lower end of the spindle 22; and it is provided with an axial circuit forming bolt 39. Also another circuit forming bolt 40 is arranged off center and extends through the plug 38.

An insulation block 41 is secured in the support 15 by screws 42, and arranged adjacent the plug 38. A circuit forming bolt 43 is secured in the block 41 and arranged to continually engage the bolt 39. A circuit forming ring 44 is secured by a bolt 45 in the block 41 and arranged to continually engage the bolt 40 to thereby form circuits from a battery 46 to the motor 24 that will not be broken when the spindle 22 is rotated.

The wiring from the battery 46 to the motor 24 is diagrammatically shown in Fig. 10. As seen therein a wire 47 connects the battery with a knife switch 48, and this switch is connected by a wire 49 with the bolt 43, that is continually in circuit with the bolt 39; and a wire 50 connects the bolt 39 with one side of the motor 24.

A wire 51 connects the other side of the motor 24 with the spring contact 34. Spring

contact 35 is connected by a wire 52 with the bolt 40 which is in continual circuit with the ring 44 and bolt 45; and the bolt 45 is connected by a wire 53 with the other side of the battery 46 so that when the switch 48 is closed and the contacts 34 and 35 are engaged a circuit will be formed through which power will be transmitted from the battery to drive the motor.

It is understood that the contacts 34 and 35 can be arranged in a switch that can be opened and closed by manual instead of the automatic means shown if so desired.

The stabilizer is constructed and arranged so that the weight of the tail 31, cage 32, heavy ball 33 and rudder 37 over-balances the propeller 27 so that when the aeroplane is tipped out of normal flying position the over-weighted tail end of the stabilizer will move by gravity to turn the stabilizer propeller in a proper direction to be operated to move the aeroplane back to its normal flying position. In other words the spindle 22 on which the housing 23 is mounted will be turned on its axis by the over-weighted tail end of the stabilizer when the aeroplane is tipped out of normal flying position.

A means is provided for securing the spindle 22 from rotating so that when desired the stabilizer can be held in a predetermined position so that its propeller can be used to aid in driving the aeroplane.

It is understood of course that when so used that the wiring connection of the motor and battery would be arranged accordingly. Such wiring is well understood in the art and is therefore not shown or described in detail.

A latch pin 54 is slidably extended through an opening 55 in the support 15; and arranged to extend into a socket 56 in the spindle 22.

The socket 56 is arranged so that when the pin 54 is secured therein that the propeller shaft 25 will be parallel with the longitudinal axis of the body 13.

A bell crank 57 is pivotally connected to the support 15 and pin 54 so that it can be operated by a draw bar 58 to release or engage the pin with the socket 56.

These parts are constructed and arranged so that in the event of an accidental fall of the aeroplane the pin 54 can be quickly released from the spindle 22 so that the stabilizer can automatically function to resist falling and return the aeroplane to a normal flying position.

The draw bar 58 is provided with teeth 59 that are adapted to be engaged with a stationary tooth 60 that is secured to the platform 17, and a spring 61 also secured to the platform 17 is arranged to normally hold the teeth engaged.

The parts for locking the spindle 22 from rotation are old and well known in the art;

and it is understood that they can be constructed in any well known way.

The operation of the stabilizer is illustrated in Figs. 7, 8 and 9. In Fig. 7 the 5 aeroplane is assumed to be falling side-wise toward the ground; in which position the stabilizer is turned cross-wise to the longitudinal axis of the aeroplane and has its propeller drawn to lift the aeroplane in the 10 direction of the short arrows to resist falling and also return the aeroplane to a poise of equilibrium. Also in Fig. 8 the aeroplane is assumed to be falling side-wise; and the stabilizer acting as in Fig. 7, which action 15 will cause the aeroplane to turn on its longitudinal axis so that its wings will be moved from the vertical line *a*, *b*, to the horizontal line *c*, *d*.

In other words one wing 13^d will move in 20 the direction of the arrows in the arc *a*, *d*; and the other wing will move in the arc *b*, *c*, until the aeroplane reaches a position of equilibrium or normal flying position; after which the stabilizer will return by 25 gravity to the position shown in Fig. 1.

In Fig. 9 the aeroplane is assumed to be falling head downward and the stabilizer is shown in a reversed position and operating to resist the fall and lift the aeroplane 30 in the direction of the short arrows which action in addition to resisting the fall of the aeroplane will also operate to turn it back into a normal flying position or to a poise of equilibrium.

35 I claim—

1. The stabilizer for aeroplanes set forth comprising a support adapted to be secured to an aeroplane; a spindle carried by said support; a housing secured to said spindle; 40 a tail secured to said housing; a cage at the tip end of said tail; electrical contacts in said cage; a ball in said cage for causing said contacts to engage; a motor in said housing; a propeller secured to the shaft of 45 said motor; and means for actuating said motor when said contacts are engaged.

2. The stabilizer for aeroplanes set forth comprising a hollow support adapted to be secured to an aeroplane; a hollow spindle carried by said support; a housing secured to 50 said spindle; a weighted tail secured to said housing; a motor in said housing; a

shaft to said motor; a propeller on said shaft, said spindle adapted to rotate so that said propeller can move in a circle; and 55 means to drive said motor to actuate said propeller.

3. The stabilizer for aeroplanes set forth comprising a hollow support adapted to be secured to an aeroplane; a hollow spindle 60 carried by said support; a housing secured to said spindle; a motor in said housing; a shaft to said motor; a propeller on said shaft; means to drive said motor to actuate said propeller; and a weighted tail arranged 65 to over-balance said propeller so that when the aeroplane is tipped out of normal flying position that said tail will turn said spindle on its axis and move said propeller in the 70 arc of a circle.

4. The stabilizer for aeroplanes set forth comprising a hollow support adapted to be secured to an aeroplane; a hollow spindle carried by said support; a housing secured to said spindle; a motor in said housing; a 75 shaft to said motor; a propeller on said shaft; a weighted tail secured to said housing that is adapted to turn said spindle on its axis when said support is tilted out of a normal position; a battery; and a wiring 80 connection between said battery and motor that is arranged to extend through said hollow support and spindle.

5. The stabilizer for aeroplanes set forth comprising a platform arranged on the body 85 of an aeroplane; a hollow support secured to said platform; a ball bearing housing secured to said support; an annular flange to said housing; brace rods extending from said flange to eye bolts secured to said platform; a ball bearing in said housing; a hollow spindle adapted to revolve in said bearing; a motor housing secured to said spindle; a motor in said housing; a shaft to said motor; a propeller on said shaft; a 90 battery; and a wiring connection between said motor and battery that is arranged to extend through said spindle and support.

In testimony whereof, I have signed my name to this specification at Los Angeles, 100 county of Los Angeles, State of California, this 10th day of March, 1925.

MARTIN PEARSON.
